John H. Brumley,
His Attorney.

UNITED STATES PATENT OFFICE.

EDWIN C. BALLMAN, OF ST. LOUIS, MISSOURI, ASSIGNOR TO BALDOR ELECTRIC COMPANY, OF ST. LOUIS, MISSOURI; A CORPORATION OF MISSOURI.

MOTOR-STARTING DEVICE.

Application filed September 21, 1922. Serial No. 589,725.

This invention relates to motor starting devices, and more particularly to such starting devices as are mounted upon the motor itself so as to be operable upon the change 5 of speed of the motor.

One of the objects of this invention, therefore, is to provide a motor starting device embodying switching means in which the arcing at the point of making and breaking 10 a circuit may be confined to certain parts, which may be renewed when worn.

Another object of this invention is to provide such switching means in which the circuit maintaining parts will be kept free 15 from corrosion by arcing.

Another object of this invention is to provide centrifugally operated switching means which shall operate reliably at a definite motor speed.

Another object of this invention is to provide centrifugally operated switching means wherein the operating effort will increase 20 after operation thereof commences.

Further objects will appear from the detail description taken in connection with the accompanying drawings, in which:

Figure 1 shows a view in elevation of a device embodying this invention;

Figure 2 is a section on line 2-2, Figure 30 1;

Figure 3 is a detail in perspective showing the bridging contact;

Figure 4 is a detail in perspective showing the means for locking the contact 35 spring; and

Figure 5 is a diagram illustrating the operation of this device.

Referring to the accompanying drawing, the device shown in Figure 1 is arranged for 40 mounting on the rotor shaft 1 of an electric motor, and comprises a disc 2 having a hub 3 and an outer peripheral flange 4. Between the hub 3 and the flange 4, therefore, an annular space is provided within which the 45 mechanism is housed.

Mounted on the inner side of the flange 50 4 at intervals around the periphery thereof and suitably insulated therefrom by means of insulating strips 5 and washers 6 in a well known manner, is a series of contact blocks 7. These blocks are fastened in place by means of screws or other suitable fastening devices 8 which may also be used to connect the circuit leads by which the current 55 is carried to and from the blocks 7.

The blocks 7 are arranged in pairs uniformly spaced about the rim 4 and between each pair, a column or rod 9 is mounted radially so as to traverse the annular space between the hub 3 and the rim 4. This column 9 passes through a suitable aperture in the rim 4 and has a bearing in the hub 3 as illustrated in Figure 2. Near the outer end of the column 9 is a groove 10 arranged so that when the column is in place, this groove 60 will lie just within the rim 4. A metallic locking piece 11 is provided with a groove 12 adapted to fit the neck of the column 9 within the groove 10. After the column has been inserted, the locking piece 11 may be 65 slipped into its place in the groove 10 and within the rim 4, so as to retain the column in place, the centrifugal force of the column assisting to retain the locking piece in place. The locking piece 11 may be provided with 70 finger notches 13 for easy manipulation. A cover 20 serves also to retain the locking pieces 11.

Mounted to slide loosely upon the column 75 9 is a bridging contact 14 having contact faces 15 adapted to engage the opposite faces of the contact block 7 for maintaining the electrical circuit between said blocks. Mounted upon the contact 14 is a pair of make and break contacts 16. The contacts 80 16 are loosely mounted upon headed pins 17 on the contact 14 and may be connected to said pins by flexible pig tails 18. The contacts 16 are thus adapted to move freely with respect to the contact 14. Said contacts 16 85 are of sufficient length to extend beyond the contact faces 15, so that when urged outwardly by centrifugal force, the contacts 16 will engage the blocks 17 before the contact faces 15 come into engagement with said 90 blocks.

Mounted on and surrounding the column 9 is a compression spring 19 which bears at one end against the contact 14 so as to hold the same against the hub 3 and at its 95 other end against the locking piece 11, serving also to hold said locking piece against dislodgement. The spring 19 is proportioned so that its length when open or uncomressed will be greater than the distance 100 L, Figure 2, between the inside of the rim 4 and the center of the shaft 1. This is desirable in order that the action of the contact 14 under the centrifugal force of rotation will be positive and take place at a 105

definite speed as will be more particularly set forth hereinafter.

As many pairs of contact blocks 7 and bridging contacts 14 with the above described accessories may be provided as there are circuits to be controlled by this device. In the accompanying drawing, three such circuits are indicated.

- In operation, the circuits to be controlled 10 are connected to the contact blocks 7 through the screws 8 as indicated above. When the motor is at rest, the springs 19 will force the bridging contacts 14 inwardly against the hub 3 to the position indicated in Figure 1. 15 As the motor attains speed, centrifugal force acting upon the contacts 14 and 16 will urge the same radially outwardly. The contacts 14 will be held against such centrifugal force by the springs 19 but the contacts 16 will be 20 urged outwardly to lie flat against the outside faces of the contacts 14 in such a position that their ends will extend beyond the faces 15. When such a speed is attained that the centrifugal force of the contacts 14 25 and their connected parts is sufficient to overcome the pressure of the springs 19, the contacts will slide radially outward along the columns 9. During such progress, the contacts 16 will first come into engagement 30 with the blocks 7, thereby making the circuit between pairs of said blocks. Thereafter the contact faces 15 will come into engagement with the blocks 7 for maintaining said circuits. As the faces 15 come into engagement 35 with the blocks 7, the ends of the contacts 16 will slide outwardly along said blocks. The circuits so made will thus be maintained so long as the motor runs at the attained speed. When the motor stops, the 40 centrifugal force acting upon the contacts 14 will be reduced and at a certain speed, the pressure of the spring 19 will be sufficient to overcome such force and the contacts 14 will be forced back again to the position shown 45 in Figure 1 and the circuits between the blocks 7 opened. During such movement, the faces 15 will break the contact with the blocks 7 before the contacts 16 disengage, so that any arcing which may take place 50 upon breaking the contact will do so at a point on the block 7 removed from the points of engagement of the faces 15 so that a clean surface is always maintained for the engagement of said faces 15. The pig tails 55 18 provide a low resistance connection between the contacts 16 through the contact 14 so that upon making or breaking the circuit, all of the current will be confined to a path through the contacts 16 as soon as the 60 faces 15 disengage with the result that there will be no supplementary arcing at the faces 15 and these faces will be maintained smooth and in a good condition for maintaining the circuit.

85 Reference will be had to the diagram, Fig-

ure 5, in order to explain the action of this device. This diagram represents a plot of the forces acting upon the contacts 14 during operation. In this diagram, displacements along the column 9 are plotted as abscissæ 70 and forces are plotted as ordinates. Thus the line OS represents the variation of the force of the spring 19 with deflection or compression along the column 9. Similarly the line GW represents the variation of 75 centrifugal force acting upon the weight 14 with its displacement along the column 9. Since the spring 19 has a greater length than the distance L as previously explained, said spring will have an initial deflection represented by OA in the diagram and will consequently exert an initial pressure represented by OC. The diagram represents conditions obtaining at that particular speed of 80 the rotor at which the centrifugal force of 85 the contact 14 is just equal to the pressure exerted by the spring 19. This centrifugal force will, therefore, also be represented by OC. This centrifugal force corresponds to a displacement of the contact 14 from the 90 center of rotation equal to GA. Now as the contact 14 moves outwardly under the action of centrifugal force, the centrifugal force acting thereon will increase along the line GW, while the resisting pressure of the 95 spring 19 will increase along the line OS, so that when the contact 14 comes into engagement with the block 7, a new position corresponding to the position B on the diagram will have been attained. In this position 100 the centrifugal force represented by OE will be greater than the spring pressure represented by OD. This shows that the centrifugal effort moving the contact 14 increases with the displacement of said contact 105 along the column 9 more rapidly than does the spring resistance thereto. A desirable result obtained by this arrangement is that as soon as the contact 14 begins to move 110 under the action of centrifugal force, said movement will accelerate and the circuit will be closed with a decided snap of the contact 14 against the blocks 7. This is a desirable result for the reason that it makes 115 for positive contact and cuts down arcing 120 to a minimum.

It will thus be seen that this invention accomplishes its objects. A circuit closing device is provided in which the contact maintaining faces will always be kept in a clean and smooth condition on account of the fact that arcing is definitely confined to the auxiliary contacts 16. The mechanical action of this device will always be positive and take place at a definite speed by virtue 125 of the action explained in connection with Figure 5. Thus, the so-called "creeping" of the contacts to contacting position is entirely avoided.

It is obvious that various changes may be 130

made in details of construction without departing from the spirit of this invention; it is, therefore, to be understood that this invention is not to be limited to the specific 5 details shown and described.

Having thus described the invention, what is claimed is:

1. In a machine of the character described, a centrifugal switch, comprising, a series of 10 main contacts, a relatively movable contact centrifugally operable to bridge certain of said main contacts, and an auxiliary contact loosely mounted on said movable contact and having a low-resistance flexible connection therewith.
2. In a machine of the character described, a centrifugal switch, comprising, a series of main contacts, a relatively movable contact centrifugally operable to bridge certain of 20 said main contacts, an auxiliary contact loosely mounted on said movable contact and extending therebeyond so as to engage said main contact in advance of said movable contact, and a low-resistance flexible connection 25 between said auxiliary contact and said movable contact.
3. In a machine of the character described, a centrifugal switch, comprising, a series of main contacts, a relatively movable contact 30 centrifugally operable to bridge certain of said main contacts, and an auxiliary contact loosely mounted on said movable contact and centrifugally operated to make and break contact with said main contact.
4. In a machine of the character described, 35 a centrifugal switch, comprising, a casing,

a series of main contacts within said casing, a centrifugally operated bridging contact adapted to engage certain of said main contacts, a guide rod for said bridging contact 40 arranged to slip into said casing, a spring supported by said rod and adapted to restrain said bridging contact, and a lock for said rod abutting said casing on the inside thereof.

5. In a machine of the character described, a centrifugal switch, comprising, a casing, a series of main contacts within said casing, a centrifugally operated bridging contact 45 adapted to engage certain of said main contacts, a guide rod for said bridging contact arranged to slip into said casing, a spring supported by said rod and adapted to restrain said bridging contact, and a lock for said rod abutting said casing on the inside 50 thereof, and retained in such abutment by said spring.

6. In a machine of the character described, a centrifugal switch, comprising, a casing, a series of main contacts within said casing, a 55 centrifugally operated bridging contact adapted to engage certain of said main contacts, a guide rod for said bridging contact arranged to slip into said casing, a spring supported by said rod and adapted to restrain 60 said bridging contact, a lock for said rod abutting said casing on the inside thereof, and a cover for said casing enclosing said lock.

In testimony whereof I affix my signature 70
this 30th day of August, 1922.

EDWIN C. BALLMAN.
